L. E. PARKER

LOGGING HOOK AND LINK

Filed April 5, 1922

UNITED STATES PATENT OFFICE.

LUKE EVERETT PARKER, OF PE ELL, WASHINGTON.

LOGGING HOOK AND LINK.

Application filed April 5, 1922. Serial No. 549,699.

To all whom it may concern:

Be it known that I, LUKE EVERETT PARKER, a citizen of the United States, and a resident of Pe Ell, in the county of Lewis 5 and State of Washington, have invented certain new and useful Improvements in Logging Hooks and Links, of which the following is a specification.

My invention relates to improvements in 10 hook and link arrangements, and it consists in the combinations, constructions and arrangements herein described and claimed.

An object of my invention is to provide 15 an extremely simple and efficient hook and link arrangement designed primarily, although not necessarily, for use in logging operations to detachably connect separated elements together in such manner as to normally prevent the connected-together parts 20 from being disconnected accidentally in service.

A further object of my invention is to provide 25 an arrangement of the character described which comprises a hook formed with no relatively movable parts and a link adapted to engage the hook when in a certain position in respect thereto and prevented from disengaging the hook when in any other position,

30 A still further object of my invention is to provide a device of the character described which is strong and durable in construction, easily adjusted and not likely to get out of order easily in the service for which intended.

Other objects and advantages will be apparent from the following description, and the novel features of the invention will be particularly outlined in the appended claims.

40 My invention is illustrated in the accompanying drawings, forming a part of this application, in which:—

Fig. 1 is a side elevation of a practical embodiment of the invention, showing a hook and a link comprised in the device in connected position,

Fig. 2 is a view at right angles to Fig. 1, showing the hook alone,

Fig. 3 is a fragmentary sectional view substantially along the line 3—3 of Fig. 1, and

Fig. 4 is a fragmentary view, showing in side elevation a modified form of hook embodying the same invention as that illustrated in the preceding views.

55 Referring now to the drawings and particularly to Figs. 1 to 3 inclusive thereof, a

hook is indicated generally at 1 and comprises the body portion 2 formed to provide an eye or loop 3 at one end and to provide a bill portion 4 at the opposite end thereof, the bill 4 being tapered toward its end and the hook being fashioned so that the end portion of the bill extends toward the eye 3, substantially in parallelism with the body 2, as is usual. The hook 1 is made of any suitable material, such as iron, steel, or the like. The front portion of the loop or eye 3 projects forwardly of the body 2, as shown.

The numeral 5 designates a chain link to which the hook 1 may be attached. A cable 6 is permanently attached to the link 5 in any suitable manner.

The link 5 is substantially elliptical in shape, as is ordinary, and is preferably formed of stock of substantially circular cross-sectional contour. In hook and link arrangements having the construction described so far, the link 5 is liable to disengage the hook 1 when the connecting element in which the hook 1 and the link 5 are incorporated becomes slack. It is of course desirable that this objectionable feature be obviated without precluding the ability to disengage the hook from the link when desired. To this end, I provide a retaining member 7 which is arranged or located between the point 8 of the bill of the hook and the forwardly projecting portion of the eye or loop 3 and the proximate side of the body 2 whereby the space between the point of the bill and the proximate portion of the retaining member 7 is restricted to such an extent that only a relatively reduced portion 9 of the link 5 can be moved therethrough to effect the connection or disconnection of the link and hook. The retaining member 7 is

90 preferably fashioned in the form of a substantially flat plate having a thickness approximately the same as the thickness or diameter of the bill 4 at its end. The inner and upper sides or edges of the flat retaining member 7 are adapted to closely contact

95 portions of the body 2 and the forwardly projecting portion of the loop or eye 3, respectively, when an integral stud 9' of non-circular cross sectional contour which ex-

100 tends from the inner edge of the retaining member 7 is projected through a transverse opening 10 through the body 2 and the end of the stud is upset at 11 to hold the inner and upper edges of the retaining member 7

105 in abutting relation to the body 2 and the lower portion of the forwardly projecting

110

part of the eye or loop 3, respectively. The opening 10 is formed to cooperate with the stud 9' so as to engage the latter to prevent rotation thereof about its axis.

5 It is to be observed at this point that the reduced portion of the link 5 is located intermediate of the length of the latter and in consequence, is not likely to be moved between the point of the bill 4 and the proximate portion of the retaining member 7 in service unless it is desired that the hook and link be disconnected, one from the other. It will be obvious that the link 5 and the hook 1 can be readily and easily connected together, when desired, and disconnected at will with equal facility. The hook 1 includes no relatively movable parts and is therefore not likely to get out of order in service or to be rendered inoperative or detrimentally affected by adverse service conditions, as when the hook becomes rusted or covered with mud, ice, or other obstructions to the service of hooks embodying moving parts, of which I am aware.

25 The retaining member 7 is preferably formed so that the front edge or side thereof lies substantially in the plane of the corresponding side of the end portion of the bill 4, thereby offering no obstruction to the link 5 when the latter and the hook 1 are moved together in the operation of connecting these elements together.

30 The retaining member 7 not only serves to prevent the link 5 being accidentally displaced from the hook 1 but in addition, strengthens the body 2 of the hook and stays or braces the forwardly extending portion of the eye or loop 3.

35 In the form of the device illustrated in Fig. 4, the retaining and strengthening member 7 is an integral part of the hook 1 and is merged into the body portion 2 and into the forwardly projecting portion of the loop 3 of the hook, as shown.

Obviously, my invention is susceptible of embodiment in forms other than those illustrated in the accompanying drawings, and I therefore consider as my own, all modifications of the forms of the device disclosed herein, which fairly fall within the scope of the appended claims.

I claim:—

1. A hook comprising a body portion provided with a bill at one end and with a loop portion at the other end thereof, the loop portion being arranged so that a portion thereof projects forwardly of the body portion, and a retaining and strengthening element positioned upon said body portion to restrict the passageway leading through the space between the bill and the body portion of the hook and extending in one direction to the forwardly projecting portion of the hook and in the opposite direction an appreciable distance along the body portion of the hook to strengthen the latter adjacent to the loop portion thereof and to stay the loop portion of the hook, the face of the retaining and strengthening element remote from the body portion of the hook lying in a plane tangent to the outer side of the bill.

2. As an article of manufacture, a hook having a substantially straight body portion provided with a bill at one end thereof and with a loop or eye at the other end thereof, said body portion having an opening of non-circular cross-sectional contour extending transversely therethrough at an appreciable distance above the plane of the end of the bill of the hook, and a substantially flat retaining member having a stud extending from one end thereof and adapted to be projected through said transverse opening and offset at its end to hold the retaining member against the body and loop portion of the hook, substantially as and for the purpose described.

LUKE EVERETT PARKER.
